UNITED STATES PATENT OFFICE.

JAMES WEATHERS, OF INDIANAPOLIS, INDIANA, ASSIGNOR OF ONE-HALF
TO JOHN A. ROBBINS, OF SAME PLACE.

COMBINED WIRE-STRETCHER AND LIFTING-JACK.

SPECIFICATION forming part of Letters Patent No. 599,465, dated February 22, 1898.

Application filed October 30, 1897. Serial No. 656,952. (No model.)

To all whom it may concern:

Be it known that I, JAMES WEATHERS, a citizen of the United States, residing at Indianapolis, in the county of Marion and State 5 of Indiana, have invented certain new and useful Improvements in a Combined Wire-Stretcher and Lifting-Jack, of which the following is a specification.

The object of this invention is to provide a 10 tool which can be used for hoisting heavy objects, such as vehicles, for the purpose of lubricating the axles, and which can also be used for stretching fence-wires and the like, the object being to provide a tool which, when 15 it is used as a lifting-jack for raising vehicles, will be light and convenient to handle and yet strong and powerful enough to lift the heaviest wagon with its heaviest load, and which will have a wide range of adaptability 20 whereby it will be capable of insertion under the axles of very low vehicles like the front axle of a phaeton or can be extended to reach axles or other objects above the usual height and lift them in an equally satisfactory 25 manner.

I accomplish the objects of the invention by the mechanism illustrated in the accompanying drawings, in which—

Figure 1 is a view in side elevation of my 30 improved tool in position for use as a lifting-jack. The near link for attaching the lever is broken away to show the pawl back of it. Fig. 2 shows the several parts of the tool in perspective and disconnected. Fig. 3 illustrates the use of the tool as a wire-stretcher, it being here shown as stretching one of the horizontal wires of a fence.

Similar letters of reference indicate like 35 parts throughout the several views of the drawings.

A represents the base, which will preferably comprise a broad board *a*, to give ample bearing-surface, and a second board *a'*, of less area, which is fastened to the lower board, 45 the two together providing the necessary strength with less weight and material than where a large board of the combined thickness of the two pieces *a a'* is used.

B is the main support or body of the machine and has an expanded base *b* with holes

whereby the standard is secured by means of the bolts *b'* to the base A. The top of the body portion terminates with the lateral parallel ears *b² b²*, which form guides for a rack-bar C, which moves longitudinally of the body 55 B, and also gives support to a pawl D and hand-lever E. Directly opposite the ears *b² b²* are the parallel ears *b³ b³*, which form a guide for the bar F.

The rack-bar C is practically the same thickness as the standard B and makes close fit between the ears *b² b²*. Its outside edge is provided with the series of ratchet-teeth C' and its lower end is provided with the integral arms *c' c'*, which are parallel and extend 60 laterally in the opposite direction from the teeth C', thereby embracing the standard B. The upper end of the rack-bar C terminates with a small platform C², on which the load to be raised will rest.

The bar F is the same in thickness as the standard B and its lower end is inserted between the arms *c' c'*, to which it is fastened by the screw *f* or by means of a bolt in place of the screw. A lug *f'* from the bar F fills the 70 space between the arms *c' c'* and finishes a shelf at a low position on the bar F, which will be used in taking hold of very low objects to be lifted. The top end of the bar F has the laterally-projected ears *f² f²*, with 75 transverse openings whereby by bolts through said openings and through a hole in the upper end of the rack-bar C the bar F is fastened to the bar C. It will thus be seen that the two bars F and C are joined together at 80 both ends and constitute a frame, between the sides of which the body B is closely embraced. The two bars support and strengthen each other. F² is a shelf or bracket integral with the bar F about midway of its length, and its 85 purpose is to enable the jack to take hold of a load lower down than could be done with the platform C².

The hand-lever E is suspended by the link-bars or double shackle *e*, which permits the 90 inner end of the lever to be lowered and hooked under one of the ratchet-teeth, and then by forcing the outer end of the lever down the rack-bar will be elevated, and any object resting on any one of the three shelves 95 100

or platforms will be lifted with the bar. The lifting power of the jack will depend on the relative length of the outer end of the lever as compared with the inner end. To enable this to be varied somewhat, I provide two holes in the lever for the fulcrum-pin. The outer hole or hole nearest the short end will enable me to reach only one tooth at a time, but the inner hole will lengthen the short arm 10 of the lever to enable me to reach two teeth at a time and is desirable where quick action is preferred at a sacrifice of power.

The pawl D has a hook at its lower end to engage the teeth of the rack-bar, and it also 15 has a handle which is bent out to throw its weight outside of its fulcrum, thereby pressing the hooked end constantly against the rack-bar, causing it to automatically engage the teeth of the bar and hold them. The handle enables the pawl to be thrown out of engagement with the teeth in lowering the load, the latter being let down with the lever a notch at a time in the same manner in which the load was elevated. To enable the pawl 20 to be drawn out and held out of engagement with the teeth of the rack-bar by the hand of the operator without his releasing his hold on the lever, I provide the rod d, one end of which is fastened to the pawl, and the other 25 end is passed through an opening through a lug e' from the lever E. The rod slides longitudinally through the lug as the lever E is raised and lowered, and the end of the rod is provided with a head which keeps it from being drawn out of the lug. By drawing the 30 rod down and holding it with a finger or thumb the pawl can be held away from the rack-bar.

The tool is serviceable as a wire-stretcher by placing the base against the side of the 35 fence-post and threading the wire through an opening through the base provided for that purpose and fastening the end of the wire to the lower end of the rack-bar, the opening m

through the rack-bar being provided for that purpose.

Having thus fully described my invention, what I claim as new, and wish to secure by Letters Patent of the United States, is—

The combination of the base A comprising the broad board a and the narrow board a' to 50 which the machine-body is fastened, an elongated body B having an expanded end with bolt-holes whereby the body is fastened to the base, and having elongated parallel ears b² at its opposite end with transverse openings 55 therethrough and parallel, opposite, shorter ears b³, the rack-bar C having the outside teeth C', the expanded end C² at one of its ends, the hole m and parallel perforated ears c' at the end opposite the expanded part and 60 on the side opposite the teeth C', said rack-bar being placed between the ears b² of the body B with the body B between the ears c' of the rack-bar, a bar F on the side of the body B opposite the rack-bar and secured between the ears c' at a point remotely adjacent 65 one end of the bar and having the ears f² at its opposite end embracing and removably secured to the adjacent end of the rack-bar, said rack-bar F having the shelves F² and f, 70 the hooked pawl D pivoted between the ears b², a lever E pivoted between the outer ends of the link-bars and having a plurality of pivot-openings at different distances from the end of the lever and having a perforated lug 75 e', and a rod d passing through the lug and secured to the pawl D, all substantially as described and specified.

In witness whereof I have hereunto set my hand and seal, at Indianapolis, Indiana, this 80 21st day of October, A. D. 1897.

JAMES WEATHERS. [L. S.]
